(57) **CLAIM**

The ornamental design for an enhanced heating system, as shown and described.

DESCRIPTION

FIG. 1 is a front perspective view of an enhanced heating system showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a right elevational view thereof; and,

FIG. 7 is a left elevational view thereof.

The broken lines in the figures depict features of the enhanced heating system that form no part of the claimed design.
